United States Patent Office

Des. 193,808
Patented Oct. 9, 1962

193,808

GRILLE

Edward C. Hallock, 86 Woodland Ave., Summit, N.J.

Filed June 26, 1962, Ser. No. 70,689

Term of patent 14 years

(Cl. D54—2)

FIG.1.

FIG.2.

FIG.3.

I claim:

The ornamental design for a grille, as shown.
